UNITED STATES PATENT OFFICE

2,134,367

TACK HOLDER

Andrei Hudiakoff, New York, N. Y.

Application January 11, 1938, Serial No. 184,372

1 Claim. (Cl. 1—49.6)

My present invention relates to a holder for tacks, nails, bolts, screws or any articles having shank and head portions.

To expedite their work, upholsterers frequently place tacks in their mouths and release them one by one as required. Holding the tacks in a shallow pan, though preferable from the sanitary point of view, is objectionable as not permitting quick and easy singular withdrawal.

10 To overcome the foregoing objections is the main object of my present invention. A more specific object is to provide a simple, effective tack holder.

15 Other objects and advantages of my invention will be apparent as the more detailed description thereof proceeds.

In the drawing, Figure 1 is an isometric view of one form of my improved tack holder, Figure 2 is a cross-sectional view of a portion of the tack holding surface employed in Figure 1, Figures 3 and 5 are views of a modification, and Figure 4 is a cross-sectional view of still another modification of my tack holder.

Referring to Figure 1, my tack holder is formed 25 of a rectangular frame 2 within which, and supported thereby, is a tack holding or mounting surface. This surface is formed of a plurality of arcuate or warped strips 4, 6, 8, which, as shown in Figure 2, form a plurality of troughs or channels 10, 12. A series of holes 14, 16, 18 are punched 30 or otherwise made in the troughs.

As shown in Figures 3 and 5, the tack holding surface may be arranged to consist of a series of angularly arranged surfaces or strips 20, 22, 35 24, 26, which, at their troughs, are provided with triangular channels or depressions 30, 32, 34. In the latter, holes are provided which are substantially larger in diameter than the shanks of the tacks 40, 42, 44, 46, 48, 50, but less in diameter 40 than the diameter of the heads of the tacks.

The supporting surface or tack plate 60, as shown in Figure 4, may be flat and be provided with a series of cylindrical channels 62, 64 into

which are punched holes for receiving the shanks of the tacks.

The tack supporting plate or surface may be supported by a rectangular frame such as shown in Figure 1, or may be carried within an open 5 box or cylinder 70, as illustrated in Figure 3. The downwardly extending edge 72 of Figure 3 is of such length that the tack points 74 do not touch the base of the container 70. In Figure 1, the rectangular frame 2 provides both downward- 10 and upwardly extending edges for the perforated tack supporting plate. The downward extension is made, as explained in connection with Figure 3, so that when the tacks are supported by their heads, their points are in free 15 space.

In the operation of my tack holder, a number of tacks 80 (Figure 1) are thrown over the supporting plate. Shaking the plate causes the tacks to take successive positions illustrated by tacks 40, 20 42, 44, 46 and 48 of Figure 5. The tacks are then in position to be quickly removed by means of a magnetic hammer 90, as shown in Figures 2 and 3.

My tack holder is preferably made of metal, 25 but it may be made of paper or other suitable material without departing from the scope of my invention.

Having thus described my invention, what I claim is:

A holder for tacks having shanks and heads comprising a member having a plurality of V-shaped troughs therein and a plurality of openings in the bottoms of the troughs whereby upon shaking said holder said tacks having shank 35 and head portions are so guided that the shank portions move into the openings and the articles are supported by their head portions against the walls of the V shaped troughs, and a rim-like structure around said member for supporting said member and for preventing the tacks from sliding off into space. 40

ANDREI HUDIAKOFF.
